BY ATTORNEY.

UNITED STATES PATENT OFFICE

GWYNNE RAYMOND, OF KANSAS CITY, MISSOURI

TELL-TALE WEAR PLATE

Application filed August 13, 1931. Serial No. 556,815.

This invention relates to tell-tale wear plates and more particularly to a removable wear plate for protecting the walls of casings such as oil and gas separators and the like from abrasion and wear incidental to impacts, friction or tangential discharge of fluids carrying abrasive material such as sand and the like.

Another important object of the invention is to provide tell-tale means for indicating exteriorly of the casing when the wear plates are about worn through so that they may be replaced before the side walls of the casing are exposed to the abrading action.

It is also an object of the invention to provide the wear plate in sections so that they may be inserted through manholes or other openings in the casing and so that individual sections may be replaced when they become worn without replacing the entire plate.

In accomplishing these and other objects of the invention, I have provided improved details of structure, the preferred form of which is illustrated in the accompanying drawing, wherein:

Fig. 1 is a sectional view through a portion of a separator illustrating a sectional wear plate embodying my invention.

Fig. 2 is a horizontal sectional view on the line 2-2, Fig. 1.

Fig. 3 is a detail sectional view through a portion of the separator wall and wear plate on the line 3-3, Fig. 2, illustrating the wear plate attaching bolts.

Fig. 4 is a detail perspective view of one of the wear plate sections.

Referring more in detail to the drawing:

1 designates the cylindrical wall of a conventional type oil and gas separator having a tangentially positioned inlet pipe 2 extending into the separator for discharging fluid circumferentially against the inner face of the wall 1. The fluid is discharged through the inlet pipe at high pressures and often

carries large quantities of sand and similar abrasive materials which quickly wear away the walls of the separator at the points of impact so that it must be replaced with a new one while the other parts thereof are in good working order.

To protect the wall of the separator I have provided an arcuate spaced wear member 3 which is attached to and supported by the wall 1 to receive the impact of the fluid and which may be formed from a material having greater wear resisting properties than the wall of the separator.

The member 3 is preferably formed of a plurality of plate sections 4, each of which has its forward edge flanged outwardly toward the wall of the tank as at 5 to slightly underlap the rear edge 6 of the adjacent section. The sections are preferably wider at their rear ends and the forward edge of each section is of the same width as the rear edge of the preceding section to provide gradually increasing width for the wear plate as the fluid stream spreads in impacting against the sections.

In order that the condensate and spray collecting on the walls of the tank above the wear plate may drain to the bottom of the separator, the wear plate sections are spaced from the walls by spacing blocks 7 to provide a channel 8 therebetween.

The sections are preferably secured adjacent their corners by fastening devices such as countersunk head bolts 9, which act as tell-tale members, extending through openings 10 in the sections and through aligning openings 11 in the wall of the separator, the heads being countersunk in the sections to lie flush with the inner faces thereof as shown at 12 in Fig. 3. The threaded shanks 13 of the bolts extend beyond the wall of the separator to accommodate nuts 14 to clamp the sections to the wall.

The bolts also preferably extend through

openings 15 in the spacing blocks to retain them in position. However, the blocks may be welded or otherwise supported by the sections.

5 Suitable gaskets or washers 16 and 17 are inserted between the spacing blocks and the wall of the separator and under the nuts 14 for sealing the openings about the bolts to provide gas and liquid tight joints.

10 In order to give warning when the plates have become worn to such an extent that they must be replaced to protect the walls of the separator, each bolt is provided with a channel 18 which is drilled longitudinally 15 through the shank to a point slightly beyond the outer face of the sections as shown in Fig. 3.

It is thus apparent that the forces wearing away the sections will also wear away 20 the bolt heads to expose the inner end of the channel, whereupon an oil spray will be discharged therethrough to the exterior of the separator, causing the bolt to act as a tell-tale member and give warning that 25 the plate sections must be replaced.

It is essential that the wearing quality of the plate and bolts be substantially the same so that the wearing away of both will be equal.

30 It is obvious that the tell-tale member may be cast integral with the wear plate and project beyond one face of the plate, and that in such construction the tell-tale member will be provided with a longitudinal bore or channel terminating at the wear limit of the plate and extending 35 through the wall of the casing. The integrally formed tell-tale member may also be used as a securing means for the plate by 40 threading the same for a nut or by welding it to the casing.

My tell-tale plate may be also used as a lining in hammer mills, coal crushers, and various other places and in event only solids 45 are handled, there will always be small particles present which will find their way through the channel in the tell-tale member when the danger point has been reached to serve as a warning.

50 What I claim and desire to secure by Letters Patent is:

1. In combination with a tank having a fluid inlet, a wear plate associated with the inlet to receive impact of fluid discharged 55 through the inlet, means for spacing the plate from a wall of the tank, and fastening means for the plate extending through the wall of the tank and having means for indicating wear on said plate.

60 2. In combination with a casing having an inlet, a wear plate comprising sections associated with the inlet to receive impact of material discharged from the inlet, means for spacing the sections from a wall 65 of the tank, and means extending through

said spacing means for indicating wear of the sections caused by abrading action of the material.

3. In combination with a tank having a fluid inlet, a wear plate secured to a wall 70 of the tank and associated with the inlet to receive impact of fluid discharged through the inlet, means spacing the wear plate from the wall of the tank, and means extending through said spacing means for indicating wear on the plate caused by abrading action of the fluid. 75

4. In combination with a tank having a fluid inlet, a wear plate associated with the inlet for receiving impact of fluid discharged through said inlet, fastening means 80 for supporting the plate having a channel for emitting a spray of the fluid exteriorly of the tank upon wear of the plate.

5. In combination with a tank having a fluid inlet and having openings therein, a wear plate associated with the inlet to receive impact of fluid discharged through the inlet and having openings aligning with the openings in the tank, bolts extending 85 through the openings for securing the wear plates to the tank, and having channels for emitting a spray of fluid upon wear of the plate. 90

6. In combination with the wall of a tank 95 having a fluid inlet and having openings therein, a wear plate associated with the inlet to receive impact of fluid discharged through the inlet, and having openings aligning with the openings in the tank wall, bolts extending through the openings for securing the wear plate, having means for indicating wear on said plate, and means on the bolts for spacing the wear plate from the wall of the tank. 100

7. In combination with a tank wall having a fluid inlet, a wear plate associated with the inlet for receiving impact of fluid discharged through said inlet, bolts for supporting the plate to the tank having means 110 for emitting a spray of the fluid exteriorly of the tank upon wear of the plate, and spacing means on the bolts for spacing the plate from the tank wall. 115

8. A wear plate for oil and gas separators comprising the combination with a tank having a tangential fluid inlet of a plate located on the inside of said tank and so situated as to receive the impact of fluid entering through said inlet, and means having longitudinally extending channels therein for securing said plate in position, said securing means being of a material having substantially the same wearing qualities as the plate, whereby said channel will be opened and a spray of fluid pass through said securing means when the plate is nearly worn through. 120

9. A wear plate composed of a plurality of adjacent sections of gradually increas- 125 130

ing width, bolts having substantially the same wearing qualities as said sections for securing the sections in position so as to be subjected to wearing action, and longitudinal channels formed in said bolts, said channels being of such length as to be opened by wearing of the bolt when the sections are nearly worn through so as to permit material from the casing to issue

10 therefrom and serve as a warning.

10. In combination with a tank having a tangentially arranged fluid inlet, wear plate associated with the inlet to receive impact of fluid discharged through the inlet and
15 having a counter-bored opening, a tell-tale member extending through the wall of the tank and having a head received in said counter-bore of the same wearing properties as the wear plate and having a longitudinal
20 bore formed from its outer end and terminating adjacent said head whereby said bore will be opened to emit a spray of fluid when a predetermined amount of the head has been worn away, and means on the tell-tale member clampingly engaging the opposite faces of the wall to prevent leakage
25 exteriorly of the tell-tale member.

In testimony whereof I affix my signature.

GWYNNE RAYMOND.
